UNITED STATES PATENT OFFICE.

BLANCH T. KINNEAR, OF CLINTON, MASSACHUSETTS.

STOVE-LID LIFTER.

No. 866,937.

Specification of Letters Patent.

Patented Sept. 24, 1907.

Application filed August 29, 1906. Serial No. 332,460.

To all whom it may concern:

Be it known that I, BLANCH T. KINNEAR, a citizen of the United States, residing at Clinton, in the county of Worcester and State of Massachusetts, have invented 5 a new and useful Stove-Lid Lifter, of which the following is a specification.

My invention relates to stove lid lifters the principal objects being to improve that type of stove lid lifters in which two handle shanks are pivoted together; to 10 provide an article of this description with means whereby one can readily insert the lifter under the lugs of an ordinary stove lid, or the like, even if the distance between the lugs varies in different lids; to provide for efficiently engaging the lugs and affording a leverage; 15 to provide for guiding the handles or shanks with respect to each other; to provide heat insulating handles; and in general to simplify and improve articles of this type.

Reference is to be had to the accompanying drawings in which,

Figure 1 is a plan of a stove lid lifter exhibiting the several features of my invention. Fig. 2 is a side elevation thereof. Fig. 3 is a bottom plan view, and Fig. 4 is a fragmentary plan view showing the device as it 25 appears when expanded into operative position.

In the type of stove lid lifters which has been referred to above, the handle shanks *a* are pivoted together on a pivot *b* and pressed apart by a spring *c*, so that when they are forced together, the feet *d*, which 30 are attached to the handles, will be spread apart to engage under the lugs of a stove lid. In this type of lifters, however, when the handles are curved, the point at which they are pivoted is located, near the bottom of the curve, in such place that the forcing together of the handles tends to tilt them about an axis which, instead of being parallel with the axis of the pivot, is at an angle thereto.

It will be readily seen by reference to Fig. 2, that on pressing the handles together, they will swing not only 40 directly toward each other in the plane of Fig. 2, but if free, they will tend to rock on an axis drawn vertically through the center of Fig. 1, thus swinging downwardly. In order to keep the parts in proper position, and guide them so they will be most efficient in 45 operation, I have provided a guide pin *c* secured to one of the shanks and passing through a perforation located in the other and curved on the arc of a circle drawn from the pivot *b* as a center. This guide pin may conveniently support the spring *c*, as shown. It will be 50 seen that it prevents any excess in downward rocking of the shanks and constrains them to move in a plane

to and from each other. In addition to this, I have made the feet curved and provided them with a pair of ears *f* which extend outwardly and constitute a fulcrum for the article when in place in the socket of the 55 stove lid. These ears also abut against each other, as is shown in Fig. 3 and at their meeting corners constitute a pivot about which the handles would rock as they move downwardly in the manner described above if it were not for the guide pin. The feet are also provided with angular projecting portions ending in projections *g* which may also act as fulcrums for the article when in position for lifting the lid.

It will be understood that the projections *g* may bear on the bottom of the socket in the lid, while the ears *f* 60 bear on the top of the lid.

In order to provide for conveniently pivoting the handles together and supporting the spring *c* and pin *e*, the two handles are preferably made V-shaped in cross section as is clearly indicated in Fig. 3. This permits 70 a lug *h* to be integrally mounted on one leg of one shank and to extend over the parallel leg of the other which carries the pivot *b* and also permits the spring and pin to be supported in a convenient manner. The lug *h* is located within the space between the outer 75 legs of the shanks. These handles end in tangs as usual on which are mounted tubular handle-grips *k* formed of heat-insulating material, preferably asbestos.

While I have illustrated and described a particular embodiment of my invention, I am aware that modifications may be made therein by any person skilled in the art without exceeding the scope of my claims.

Having thus fully described my invention, what I claim and desire to secure by Letters Patent is:

1. As an article of manufacture, a stove lid lifter, comprising a pair of pivotally connected shanks each having a curved foot, the two curved feet together constituting means for engaging under lugs in a stove lid or the like, and having an angular bottom portion and outwardly extending ears meeting at their edges and each constituting a fulcrum for the other. 85

2. As an article of manufacture, a stove lid lifter, comprising a pair of pivotally connected shanks, each having a curved foot, the two curved feet together constituting means for engaging under lugs in a stove lid or the like, 95 and having an angular bottom portion and outwardly extending ears meeting at their edges and each constituting a fulcrum for the other, said shanks being provided with tangs, and a handle grip mounted on each tang.

In testimony whereof I have hereunto set my hand, in 100 the presence of two subscribing witnesses.

BLANCH T. KINNEAR.
